CLAIM

I claim the ornamental design for a color LED film antenna, as shown and described.

DESCRIPTION

FIG. 1 is a perspective view of a color LED film antenna; FIG. 2 is a right side elevational view thereof, a left side view being a mirror image thereof;

FIG. 3 is a front elevational view thereof;

FIG. 4 is a rear elevational view thereof;

FIG. 5 is a top plan view thereof; and,

FIG. 6 is a bottom plan view thereof.

The dashed lines in the drawings are for purposes of showing environment and do not form part of the claimed invention.
